UNITED STATES PATENT OFFICE.

JULIUS L. CABLE, OF BOSTON, MASSACHUSETTS, ASSIGNOR TO THE CABLE CORPORATION, OF BOSTON, MASSACHUSETTS, A CORPORATION OF MASSACHUSETTS.

FOLDING COT.

Application filed August 6, 1925. Serial No. 48,621.

This invention relates to certain improvements in folding cots of the type shown in my prior Patent #1,507,906, in which the frame and legs are formed from sheet metal shaped in semi-tubular, or channel form.

An objection to cots of this type which employ end bars, which must be placed in position after the cot has been unfolded, is that the bed portion or canvas must be drawn tight lengthwise of the cot, and this is done by the leverage afforded by pulling on an end bar until the canvas has been sufficiently stretched to permit the bar to be locked in position. As it ordinarily requires considerable strength to do this, many users have found the difficulty of setting up the cot a serious objection.

In cots of this type, the canvas has usually been secured in place by forming loops therein through which the side bars are passed before they are riveted to the legs. In case the canvas has to be renewed, as it would be impractical to remove the rivets, the only practical method in such case has been to sew up the loops by hand after the canvas has been placed in position, which is a somewhat expensive operation.

The objects of my invention are to provide an improved form of cot of the type referred to, in which the use of end bars may be avoided and in connection with which means may be provided for so supporting one end portion of the canvas that it will serve as a raised support for the head of a person thereon. Also to provide a cot in which the canvas or other textile support may be readily renewed and will be so supported that the width of the cot may be substantially increased and, at the same time, the area of the textile material which is employed may be substantially reduced. Also to improve the form of pivotal connection between the frame and the legs by decreasing the cost of manufacture without decreasing the strength of the construction.

I accomplish these objects in the manner hereinafter described and as illustrated in the accompanying drawings in which:

Figs. 1 and 2 are, respectively, a plan and a side elevation of a cot embodying my invention, the parts being shown in the unfolded position.

Fig. 3 is an elevation showing the cot in folded position.

Fig. 4 is a plan view of the middle portion of the cot partly folded.

Fig. 5 is a detail perspective view, partly in section at $x-x$ of Fig. 1, showing the form of connection of the canvas and side bars.

Figs. 6 to 9 are detail views of the form of connection between each leg and side rail, Fig. 9 being a section on line $y-y$ of Fig. 6.

Fig. 10 is a detail view of the means for supporting the head end of the canvas.

Fig. 11 is a detail view of the edge portion of the canvas.

Fig. 12 is a detail view of one of the end leg joints.

Fig. 13 is a section at line $z-z$ of Fig. 1.

In general construction and arrangement the cot is the same as shown in my said prior patent, and comprises two pairs of side rails or bars 1, and three pairs of crossed pivotally connected legs 2, one pair being arranged in the middle and the others at the ends. The legs are formed of strips of channel form, or semi-tubular metal strips and the legs of each pair are arranged side by side and a pivot 3 is passed through both sides of each leg of a pair at the middle thereof, the ends being riveted to make the connection permanent. The end portions of each side rail are also of semi-tubular form, the middle portion being semi-cylindrical and the sides parallel, and the sides of the intermediate portions of the rails, or portions between said end portions, are curved inwardly, in continuation of the cylindrical formation of the middle portion of the rail, until the edges of the strip are in such close proximity so as to form retaining lips 1^a and to provide a narrow slot, the width of which is only slightly greater than the thickness of the canvas 4 which is employed as the bed portion of the cot. Before the canvas or other suitable flexible sheet material is placed in position in the cot the longitudinal edge portions of the strip are folded about a cord 5 and sewed closely adjacent thereto, and, in applying the canvas to the cot, after the metal parts thereof are assembled, one end of the canvas at its opposite edges, is drawn into the slots between the lips 1^a, at one end of each side rail at the foot or head end of the cot, so that the edge portions, which are enlarged by the cord 5 at each longitudinal edge, pass into the side rails, as shown in Fig. 5. The canvas is thus

drawn through the slots of each pair of side rails, so that it extends the entire length of the cot and is retained within the rails at all points except those opposite the points of connection in the legs, as shown in Fig. 1.

The form of connection between each leg and side rail end portion is similar to that shown in my application Serial No. 3583, but differs therefrom in certain details. As shown in Figs. 6 to 8, the form of T-head connector between the legs and rails which I employ consists of two sheet metal plates or sections which comprise complementary semi-cylindrical portions 6 and 7 which are adapted to be fitted together to form a cylindrical shaped head having an external diameter corresponding to the internal diameter, or the distance between the inner surfaces of the parallel sides of the rails 1, at their end portions, so that it may be closely fitted therein.

The head portions 6 and 7 are each provided with an ear 8 and 9, respectively, said ears extending at right angles thereto and being so arranged that their adjacent sides lie flat against each other in the plane of the meeting edges of the head portions, as shown in Fig. 8. The side edges of said ears are perpendicular to the head portions, and flanges 10 are formed on the side edges of ear 8, which project away from the ear 9, and flanges 11 are formed on the side edges of ear 9, which extend flush with the edges of flanges 10 and are closely fitted to the outer sides thereof.

The side portions of each leg 2, at its upper end, are bent at right angles away from each other to form flanges 12, the edges of which are parallel and are adapted to fit closely between the inner or adjacent sides of flanges 10, when the parts are assembled, as shown in Fig. 9, in which position the upper ends of the flanges 12 will be engaged with the head portion 7.

As thus arranged the ears 8 and 9 are firmly clamped together and to the flanges 12 by rivets 13, which extend therethrough thereby attaching the leg to the head portions 6 and 7, and holding the latter in position to form a cylindrically shaped head.

It will be observed that, with this construction the parts are firmly braced against strains in all directions. As the parts are formed by means of dies they will be uniform, but, to prevent misplacement of the sections when connected, the ears 8 are intended to form projections 14 and the ears 9 are punched out to form apertures, or recesses 15, so that, when the sections are assembled, the projections 14 will enter the recesses 15 and make the meeting edges of the cylindrical portions perfectly flush, as shown in Fig. 8.

In assembling the legs thus provided with T-heads, the cylindrical portion is inserted

within the end portion of each side rail, the heads on the middle legs being disposed within the adjacent portions of the rails and pivotally connected thereto near each end of the head by bolts 16, which extend through the sides of the rail and both sides of the head at the middle longitudinal line of each semi-cylindrical portion thereof. The end legs are connected to the ends of the side rails in like manner by pivot bolts 17, which pass through the rails in such a position that when the head is held within the rail in position of alignment, the opposite end portion of the head from the pivot will extend for a substantial distance beyond the end of the rail, as shown in Figs. 1 and 2. A stay piece consisting of a flat metal strip 18 is connected by rivets, or other suitable means, to the under side of the canvas 4, at each corner thereof, close to, and in parallel relation with the adjacent end edges of the canvas, and each stay piece is extended for a short distance beyond the adjacent side edge of the canvas and is flexibly connected to the end portion of the adjacent T-head, which projects beyond the adjacent end of the side bar, by means of a split rivet 19, or other suitable means, which permits convenient removal in case it is necessary to disconnect the canvas from the frame, for the purpose of removal. At the end of the cot designed to be the foot end, the arrangement is such that, when the cot is unfolded and in position for use, the canvas will be drawn between the stays as tightly as at other points.

At the head end, each leg has a stiff metal post, or strut 20 connected thereto by a pivot 21 at a suitable distance from the upper end thereof, and each stay piece 18 has a small hole or recess 22 therein adapted to receive the opposite end of the strut 20, which may be somewhat pointed as shown, when the latter is in an approximately vertical position, as shown in Fig. 10, in which position the stay piece will be held in an upwardly inclined position from the leg. With this arrangement, when the cot is unfolded and before the side rails are spread apart to the fullest extent the struts 20 will be placed in the position of Fig. 10, thereby supporting the canvas between the stays, when the cot is fully open, at a substantial distance above the level of the side rails, as shown in Figs. 1 and 2, so that a support for the head of the person reclining on the cot, is provided. When the cot is folded, the struts are swung out of engagement with the stays and folded with the legs.

In folding the cot, the side rails are first swung together, then the end legs are folded against the adjacent rails, and then the whole frame is folded at the middle joints. In performing this last folding operation, the middle portion of the canvas is drawn about

the middle joints, so that the canvas is drawn from the ends of the cot frame to some extent, and I have ascertained that, when the canvas is permanently attached to the frame at each end, complete folding of the cot is not possible without placing undue strain on the canvas, unless sufficient slack canvas is given off at the ends to offset that taken up by the middle joints. For this reason the T-head at the end of each side bar is pivotally connected thereto at such a point that the opposite end from the pivotally connected end extends to a substantial extent beyond the adjacent end of the side bar, and the canvas is connected to this end portion as above described. With this arrangement, when the end legs are folded, the points at which the canvas, at its corners, are attached will be carried from the dotted line 20 position of Fig. 12, towards the middle joint, to the full line position thereof, thereby providing sufficient slack canvas to permit folding.

As shown in Fig. 6, the ears 8, 9 are located somewhat nearer one end of the semi-cylindrical portions 6, 7 than the others, the purpose of this arrangement being to permit both parts which form the T-heads to be used on any one of the legs and to provide 30 for the different setting thereof in the side bars to compensate for the off-set position of each leg of a pair with relation to each other, due to the fact that they are arranged to swing in different planes rather than in the same plane. That is, as shown in Fig. 4, the T-head which is connected to the side rail at one side is in the correct position for one leg of the pair and the T-head which is connected to the opposite side rail is in the correct position for the other leg of the pair, while the ends of the heads and pivots therein will be directly opposite. For the same reason, the distances which the heads at the ends of the cot will project beyond the ends of the side rails will be the same.

The metal from which the sections of the connecting heads are formed may be die cut from small pieces of sheet metal which ordinarily would be waste stock, so that a substantial reduction in manufacturing cost may be made, as compared with a construction which would have to be made from whole stock, and at the same time the construction is as strong as my previous constructions, and is capable of being more easily assembled in the process of manufacture.

The provision of means whereby the end bars may be omitted substantially reduces the weight and cost of the cot, and at the same time greatly increases the facility with which it may be set up, and the provision of means for elevating the head end of the canvas when desired is of substantial advantage.

The above described means for attaching the canvas, or other sheet material forming the bed, to the side rail, is advantageous in several respects as compared with my previous arrangement, as the width of the cot may 70 be substantially increased and at the same time the width of the canvas employed may be reduced. Also the manufacturing cost is less and the construction permits new canvas to be placed in the cot without difficulty.

I claim:

1. A channel form metal leg adapted for use in a cot having a channel form metal side rail, a pair of metal plate sections having complementary head portions adapted to fit corresponding opposite portions of the side rail interiorly and to be connected thereto, and having ears extending from said head portions in transverse relation and 80 arranged to be held one against the other when said head portions are fitted within the rail and means for clamping said ear portions to the leg at one side thereof.

2. A channel form metal leg adapted for use in a cot having a channel form metal side rail, a pair of metal plate sections having complementary, semi-cylindrically shaped head portions corresponding exteriorly to the interior surface of a portion of the side rail and adapted to be fitted therein and to receive a pivot for engaging the sides of the rail, and having ear portions projecting transversely from said head portions and engaged with each other in parallel relation 100 and extending longitudinally of the leg, and means for clamping said ear portions to each other and to the leg.

3. A channel form metal leg adapted for use in a cot having a channel form side rail, 105 said leg having the edge portions of its sides bent outwardly to form oppositely disposed flanges, a connector for said rail and leg consisting of a pair of metal plates each shaped to provide complementary head portions 110 adapted to be fitted within an end portion of the rail and to be pivotally connected thereto, and ear portions extending transversely from said head portions and adapted to be held in surface engagement with each 115 other and with the leg flanges when said head portions are in complementary position, and means for clamping said ear portion and leg flanges together.

4. A channel form metal leg adapted for 120 use in a cot having a channel form metal side rail, said leg having the edge portions of its sides bent outwardly to form oppositely disposed flanges, a pair of metal plate sections each comprising a half channel 125 form head portion corresponding exteriorly to the interior surfaces of corresponding portions of the side rail into which said head portions are fitted, and ear portions projecting transversely from said head portions and 130

4
arranged to be engaged with each other in parallel relation when the head portions are fitted within said rail, and means clamping said ear portions together and to said flanges to rigidly attach said plate sections thereto.

5. A channel form metal leg adapted for use in a cot having a channel form metal side rail, said leg having the edge portions of its sides at its upper end bent outwardly to form 10 oppositely disposed flanges, a pair of metal plate sections each comprising a half channel form head portion corresponding exteriorly to the interior surface of corresponding portions of the side rail and into which 15 said head portions are adapted to be fitted, and ear portions projecting transversely from said head portions and arranged to be held with their adjacent sides in contact with each other when the edges of the head 20 portions are engaged and means for clamping said ear portions to said flanges in longitudinal relation.

6. A channel form metal leg adapted for use in a cot having a channel form metal 25 side rail, said leg having the edge portions of its sides bent outwardly to form oppositely disposed flanges, a connector for said rail and leg consisting of a pair of metal plates each shaped to provide complemental 30 head portions adapted to be fitted within an end portion of the said rail and to be pivotally connected thereto and ear portions extending transversely from said head portions and adapted to be held in surface engage-

ment with each other and with the leg 35 flanges when said head portions are in complemental position, one of said ear portions having longitudinally extending flanges projecting opposite the edges of said leg flanges and engaged therewith and means extending 40 through said ear portions and leg flange to clamp the same together.

7. A channel form metal leg adapted for use in a cot having a channel form metal side rail, said leg having the edge portions 45 of its sides bent outwardly to form oppositely disposed flanges, a connector for said rail and leg consisting of a pair of metal plates each shaped to provide complemental 50 head portions adapted to be fitted within an end portion of the side rail and to be pivotally connected thereto, and ear portions extending transversely from said head portions and adapted to be held in surface engagement 55 with each other and with the leg flanges when said head portions are in complemental position, each of said ear portions having flanges extending longitudinally of their edges, the flanges of the ear portion next the leg being directly engaged with the 60 edges of its flanges and being overlapped by the flanges of the other ear portion and means for clamping said ear portions and leg flanges together.

In testimony whereof, I have signed my 65 name to this specification.

JULIUS L. CABLE.
